UNITED STATES PATENT OFFICE.

GEORG ROTH, OF ZURICH, SWITZERLAND, ASSIGNOR TO AKTIEN GESELLSCHAFT FÜR TECHNISCHE INDUSTRIE, OF ZURICH, SWITZERLAND, A CORPORATION.

ADDING-MACHINE.

No. 886,543.

Specification of Letters Patent.

Patented May 5, 1908.

Application filed June 8, 1906. Serial No. 320,764.

To all whom it may concern:

Be it known that I, GEORG ROTH, a citizen of the Swiss Republic, residing at Zurich, in Switzerland, have invented certain new and useful Improvements in Adding-Machines, of which the following is a specification.

This invention relates to improvements in adding machines and comprises improved mechanism for the transmission of the key-movements to the adding wheels, by direct gearing with the operating wheels through common driving means, said mechanism being adapted to be locked should the keys be imperfectly struck or depressed.

15 The improvements are shown in the annexed drawing in which

Figure 1 is a front view of the adding machine showing its front part in section on the line I—I of Fig. 2. Fig. 2 is a longitudinal section on the line II—II of Fig. 4. Fig. 3 is a partial side-view. Fig. 4 a plan view with parts partially broken away, and Figs. 5 to 7 are detail views of parts.

Similar reference numerals are used to indicate corresponding parts throughout the several views.

On a shaft 17 having bearings in the machine-frame 18 are rotatably mounted the key-levers 1 to 9 and a lever 19 provided 30 with a cross bar 44. The lever 19 in Fig. 2 comes behind the key-lever 1 for the greater part of its length, and the cross bar 44, shown in section, projects from the lower edge of the lever 19 and extends crosswise 35 under the key-levers. The toothed end portion 10 of the lever 19 projects beyond the lever 1 at the end farthest from the shaft 17, and the relation of the end portions of the two levers is more clearly shown in Fig. 6. 40 Each of said levers bears near its center of motion on a helical spring 20 and said transverse bar 44 serves as a support for the key-levers. By means of said springs 20, the lever 19 and the key-levers 1 to 9 are normally held in their upper initial position which is limited by an abutment 25.

The front end of the lever 19 is formed as a toothed segment 10 adapted to mesh with a toothed wheel 11 mounted on the shaft 13, 50 also carrying a ratchet wheel 12 engaged by a pawl 22 pivoted to a driving wheel 14 mounted loosely on said shaft 13 so that said driving wheel 14 is revolved by the rotation of the shaft 13 on depressing a key, whereas

it remains free on movement in the opposite direction.

The keys 1 to 9 carrying the corresponding numerals or symbols are each provided at their free end with a downwardly extending nose 23 that on each key being of a different length, proportionally to the value of the figures 1 to 9. Below the noses 23 is pivotally mounted at 78 in the machine frame a bow or frame 24 having an arm 26 extending beyond the center of rotation said bow having a tooth 26^a at its free end and being so weighted that the transverse portion 27 at the opposite end of the bow is normally held in its upper position.

On a stationary shaft 16 parallel to the aforesaid shaft 13 a plurality of toothed-wheel couples 15, 77, are loosely mounted each having ten teeth and connected in couples, the first toothed wheel lying on the right or behind the first couple being engaged by the driving wheel 14. Meshing with the wheels 77 of said toothed couples are the toothed wheels 67 each connected rigidly with a number disk 59 and disk 68. (See Figs. 2 and 4.) The said wheels 67 are mounted on a shaft 58 and also each have ten teeth. The disk 68 is provided with a tooth 69, and, adjacent the latter, with a lateral recess 70. With the exception of the first toothed-wheel couple each of the latter is provided with a ratchet wheel 37 engaged by a toothed lever 38 in such a manner that the latter lies between the disk 68 and said ratchet wheel. (See Fig. 2.) The said lever 38 is rotatably mounted on a shaft 40 and is pressed on to the ratchet wheel 37 by a spring 39. The shaft 58 carrying the number disks 59 has bearings in a separate casing 21 adapted to have sliding movement in the machine-frame 18 by means of a guide rod 56. In said casing 21 is also mounted a rotatable shaft 55 on which are fixed hooked levers 64 and flat-springs 65 resting at their free ends on the toothed wheels 67 that is to say on one tooth thereof. (See Figs. 2 and 5.) The shaft 55 also carries a toothed catch 62 adapted to engage a recess 61 in a disk 60 secured on the shaft 58, said catch being under the influence of a helical tension spring 54. In place of the springs 65 spring-actuated levers may be used.

The number of disks 59 and toothed wheel couples 15 may be optional and is chosen

according to the number of rows of figures to be added.

According to the number of number-disks, inspection apertures 57 and recesses 76 are 5 provided in the casing 21, the said recesses being adapted to be engaged by pins or pointers 71 on the machine-frame 18 and also by a propeller 72 arranged on said frame. The said propeller 72 consists of a plate 10 revolvably mounted on a stationary pin or pivot 74, and having two inclined blades or projections 73 arranged at angles with regard to each other. The working surface of said projections is segment shaped; the axis 15 of the segment lying in the center of rotation of the propeller.

The projections 73 engage the recesses 76 in such a manner that by the rotation of the propeller in the direction indicated by the arrow in Fig. 3 the casing 21 is raised that is rotated towards the rear and again lowered, the aforesaid guide-rod 56 forming the fulcrum.

As the projections 73 are at angles to each other, the casing 21 is shifted at each half rotation, for a distance corresponding to that between two recesses 76 the following projection coming into engagement with the next recess, whereas at the same time the pins 71 come into engagement with the next following recess.

It is obvious that the propeller may have only a single or more than two projections 73.

The above described displacement of the casing 21 that is of the adding wheel gearing with regard to the toothed wheel couples 15, 77, takes place to the right as often as a row of figures is to be added viz. as often as more than one unit exists in one of the numbers to be added. At the commencement of the addition the casing 21 is suitably engaged by its first recess on the right so that the first pin 71 formed as a pointer is directed towards the inspection aperture.

45 The number disks 59 are provided at their peripheries with the figures 0-9 and in order to bring same into the zero-position, that is into such a position that in each inspection aperture 57 the figure "0" appears, the number-disk shaft 58 extends through the end wall of the casing 21 and is provided exteriorly with a knob 66. If this knob 66 is rotated in the direction indicated by the arrow in Fig. 3 the lever 62 becomes disengaged from the recess 61 in the disk 60 and slides upon the normal periphery thereof of the same (Fig. 5). The shaft 55 is thus rotated and the locking springs 65 are consequently raised so that the toothed wheels 67 are released, and the hooked-levers 64 project into the path of abutment pins 63 projecting laterally from the number wheels at suitable points. By the rotation of the shaft 58 and disk 60 the number wheels 59, toothed-wheels 67 and single toothed disks 68 are re-

70 volved by frictional contact with the said disk 60, until their abutment pins 63 engage the corresponding hooked-levers 64 whereupon said number wheels are locked. The rotation of the shaft 58 and disk 60 is continued until the lever 62 again engages the recess 61 in the disk 60 that is to say until a complete revolution has been performed, during which all the number wheels reach the zero-position in a shorter or longer time. On the engagement 75 of the lever 62 into the recess 61 the hooked lever 64 is returned to the position of rest and the locking springs 65 into their operative position.

When a key is depressed the lever 19 and toothed segment 10 are consequently moved downwards until nose 23 on said key-lever strikes against the transverse portion 27 of the bow 24 whereby this part of the bow is depressed and the tooth 26^a moved upwards 80 into engagement with the teeth of the driving wheel 14 which is thereby locked.

85 The driving wheel is revolved through a longer or shorter distance by the toothed segment 10 according to the length of the noses 23 this distance corresponding to the proportion or value of the figures so that if, for instance the key "3" be depressed the first wheel 15 of the toothed wheel couple is rotated through three teeth and if the key "7" 90 is depressed through seven teeth.

95 At the commencement of the addition the toothed wheel 67 of the first right hand number wheel meshes with the second toothed wheel 77 of the first couple so that if keys "3" and "7" be depressed the figures 3 and 0 appear after each other in the first inspection aperture. After a complete revolution of the number wheels has been performed, the tooth 69 engages the first toothed wheel 15 of the second couple so that the latter is rotated through one tooth. The second wheel 77 of this couple meshes with the toothed wheel 67 of the second number disk thus causing the figure "1" to appear in the 100 inspection aperture belonging thereto (to the left of that first mentioned) so that in the two apertures the sum 10 of 3+7 is indicated.

105 When during the progress of the addition the second number wheel is rotated through ten units or teeth the corresponding tooth 69 acts on the toothed wheel 15 of the third couple the second wheel 77 of which meshes with the third number wheel and rotates 110 the same through the corresponding number of units.

115 When one row of figures has been dealt with, the casing 21 is displaced to the right by a half-revolution of the propeller 72 so that the second number wheel comes into engagement with the first toothed wheel couple and the first number wheel is put out of action. The adding wheels are locked in 120 the corresponding position by means of the 130

levers 38. When however the toothed wheel couple and therefore the ratchet-wheel 37 are rotated by the tooth 69 the lever 38 may pass, against the action of its spring 39, into the recess 70 in the single toothed disk 68 which recess passes at this moment, until said lever 38 again engages the next tooth of the ratchet wheel 37.

In order to control the machine when the 10 keys are struck negligently and to avoid re-commencing the addition an angle-lever 45, 46 is mounted in a shaft 43, the arm 46 of said lever being provided with teeth 46^a and carrying an abutment 48, Figs. 6 and 7, the 15 latter having a recess 80 for passage of the segment lever 19.

Owing to the weight of the arm 46 being greater than that of the arm 45, the latter normally lies with its upper inclined end 20 against the cross bar 44 of the segment lever 19. The noses 23 of the key-levers 1 to 9 are each provided with a stud 41 adapted to engage the hooked end of the abutment 48. The segment-lever 19 is provided with a 25 spring catch 47 lying in the path of the angle-lever 45, 46. The arm 45 is provided with a pivoted catch 49 movable only in an upward direction and engaging a toothed lever 51, the latter being mounted on a shaft 42 supported in the frame 18 and connected by a link 50 to a slotted arm 52 of the bow 24, the latter therefore holding the catch 51 in position.

When a key is depressed the cross bar 44 30 forces backwards the arm 45 so that, as shown in Fig. 6, the catch 49 engages the toothed lever 51 and the catch 47 the teeth 46^a of the arm 46. At the same time the abutment 48 is moved beneath the studs 41 35 of the other key-lever-noses 23 whereas the stud of the operated key lever is already below the point of action of the abutment 48. Should the respective key be released before its nose 23 has struck the transverse portion 40 of the bow 24 the stud 41 on this key strikes from below against the abutment 48 and prevents the key from completely returning to its initial position and at the same time the segment-lever 19 is prevented from 45 returning by the engagement of its catch 47 with the teeth 46^a of the arm 46. Owing to the consequent locking of the key-levers it is impossible to depress any other lever than that one the stud 41 of which is below the 50 point of action of the abutment 48, this lever being easily identified since it is in a lower plane than the remainder. As the segment-lever 19 is held in its lowest position, the mistake can be corrected by completely depressing 55 the key lever and the locking device will be put out of action without danger of transferring a unit too many or too few. If the key struck did not correspond to the value desired, the difference can be borne in mind 60 at the next key-stroke since the value of the

key previously depressed can be ascertained by means of the locking device.

When the key is completely depressed the nose 23 thereof strikes the transverse part 27 of the bow 24 so that the latter is rocked about its pivotal point 78 and its tooth 26^a 70 caused to engage the teeth of the driving wheel 14 and lock the same, whereas the arm 52 link 50 and the toothed lever 51 are moved downwards so that the catch 49 is disengaged 75 from the toothed lever 51 and the arm 45 of the angle-lever 45, 46 moves back whereupon the catch 47 is disengaged from the abutment 48 and all the parts are permitted to return to their original positions. For stopping the driving wheel 14 an angle-lever 30, 80 34 pivoted at 33 is provided. The arm 30 of said lever has rotatably secured thereto a shoe 29 and the arm 34 under the action of a spring 31 in such a manner that the shoe 29 85 is pressed against the periphery 79 of the driving wheel 14; the shoe 29 is preferably provided with a sole or surface 32 of caoutchouc or similar material.

The machine is provided with a casing 25 90 curved at its front part to form a support for the hand.

What I claim as my invention and desire to secure by Letters Patent of the United States is:—

1. In an adding machine, the combination, with a stationary frame, of a series of finger-key levers pivoted in the said frame and provided with projections which limit their downward movement in a prearranged proportion, a lever also pivoted in the said frame and provided with a toothed segment and having a bar with which the said finger-key levers engage, a toothed transferring wheel journaled in the said frame in gear with the 100 said segment, and a locking-device for engaging the said wheel, said locking-device being pivoted in the said frame and provided with a transverse stop arranged under the said projections and operating to lock the said 105 wheel and to limit the downward movement of the said levers simultaneously.

2. In an adding machine, the combination, with a series of pivoted finger key-levers provided with stops which limit their downward movement in a prearranged proportion, of a single lever pivoted at one end and provided at its other end with a toothed segment and having a bar at its middle part which extends crosswise under the said key-levers, a toothed 110 wheel engaging with the said segment, a pivoted angle-lever operated by the said lever when moved downward, said angle-lever being provided with a stop which prevents all the keys which have not been depressed with 115 the said lever from being depressed accidentally, and registering mechanism operated by the said wheel.

3. In an adding machine, the combination, with a series of pivoted finger key-levers pro- 120

vided with stops which limit their downward movement in a prearranged proportion, of a single lever pivoted at one end and provided at its other end with a toothed segment and 5 having a bar at its middle part which extends crosswise under the said key-levers, a toothed wheel engaging with the said segment, a locking-device operated by each of the said key-levers and engaging with the said wheel, a 10 pivoted angle-lever operated by the said lever when moved downward purposely by any one key-lever, said angle-lever being provided with a stop which then prevents the accidental downward movement of the re- 15 maining key-levers, catch mechanism connected with the said locking-device and with the said angle-lever and preventing the said key-lever which was moved purposely from being raised unless it has been depressed sufficiently to actuate the said locking-device, and registering mechanism operated by the 20 said wheel.

4. In an adding machine, the combination, with a shaft 16, and toothed wheels 15 and 77 25 secured together in couples, each said couple being journaled on the said shaft 16; of driving mechanism for revolving one of the said wheels 15 step by step, a shaft 58, toothed wheels 67 mounted on the shaft 58, 30 and engaging with the said toothed wheels 77, number disks secured to the said wheels 67, disks 68 each having a single tooth, said disks being also secured to the said wheels 67 and operating the wheels 15 of the next ad- 35 jacent couples once during each revolution of the said wheels 67 to which they are secured, and means for locking and releasing the said toothed wheels.

5. In an adding machine, the combination, 40 with a shaft 16, and toothed wheels 15 and 77 secured together in couples, each said couple being journaled on the said shaft 16; of driving mechanism for revolving one of the said wheels 15 step by step, a shaft 58, 45 a casing supporting the said shaft 58 independent of the said shaft 16 and its said wheels, a revoluble propeller for moving the said casing step by step longitudinally of the said shaft 16, toothed wheels 67 mounted on 50 the shaft 58 and engaging with the said toothed wheels 77, number disks secured to the said wheels 67, disks 68 each having a single tooth, said disks being also secured to the said wheels 67 and operating the 55 wheels 15 of the next adjacent couples once during each revolution of the said wheels 67 to which they are secured, and means for locking and releasing the said toothed wheels.

6. In an adding machine the combination 60 with a series of keys noses of different lengths at the free ends of said keys, a spring sup-

ported lever operated by said keys; a common driving wheel adapted to be rotated by said lever through distances corresponding to the value of the keys operated determined by 65 the length of said noses, a pivoted bow adapted to be engaged by said noses to lock the driving wheel and limit the movement of the keys adding wheels actuated by said driving wheel, and means for locking the spring supported lever on incomplete depression of a key comprising an angle lever and catches adapted to lock said angle lever to the spring supported lever and bow aforesaid substantially as described. 70

7. In an adding machine the combination with a series of keys noses of different lengths at the free ends of said keys, a spring supported lever operated by said keys, a common driving wheel adapted to be rotated by 80 said lever, through distances corresponding to the value of the keys operated determined by the length of said noses, a pivoted bow adapted to be engaged by said noses to lock the driving wheel and limit the movement of 85 the keys, adding wheels actuated by said driving wheel, means for locking the spring supported lever on incomplete depression of a key comprising an angle lever and catches adapted to lock said angle lever to the spring supported lever and bow aforesaid, a slid- 90 able casing containing the adding wheels aforesaid and having recesses along an edge thereof and means for laterally displacing said casing and adding wheels comprising a rotatable propeller having inclined projections 95 adapted to engage the aforesaid recesses substantially as described.

8. In an adding machine the combination with a series of keys of a spring supported 100 lever co-acting therewith, a common driving wheel adapted to be rotated by said lever through distances corresponding to the value of the keys operated, means for locking said driving wheel after each operation of the 105 keys, means for locking the aforesaid spring supported lever on incomplete depression of a key, adding wheels, intermediate gear wheels between the adding wheels, and common driving wheel, a slid- 110 able casing containing said adding wheels, means for laterally displacing said casing and adding wheels and means for suitably locking and releasing said adding wheels and intermediate gear wheels substantially as described. 115

In witness whereof I have signed this specification in the presence of two witnesses.

GEORG ROTH.
